FOLDING FURNITURE

Amos G. Parry, Granville, N. Y., assignor to Telescope Folding Furniture Company, Incorporated, Granville, N. Y., a corporation of New York

Application October 31, 1932, Serial No. 640,403

2 Claims. (Cl. 155—117)

This invention relates to structures such as chairs which have side or rest arms, and especially to means for maintaining these side or rest arms in spaced relation.

5 Heretofore in the manufacture of chairs having side or rest arms, it was customary to secure the inner ends of the side arms to the back of the chair and the outer ends thereof to the upper ends of upright supports, the lower ends of which were 10 in turn secured to the seat of the chair. Such means of supporting the rest arms were unsatisfactory however, due to the fact that the upright supports were maintained in spaced relation at only two places throughout their length, 15 namely where they were secured to the outer ends of the rest arms and where they were secured to the seat. Under such conditions when the side arms were subjected to side thrusts, the upright supports acted as levers, and the rest arms 20 tended to rotate about the lower upright supports.

An object of the present invention is to provide means for maintaining the rest arms of a chair in spaced relation when the rest arms are subjected to side thrusts.

25 In accordance with the present invention, this and other objects are attained by maintaining the supporting members in spaced relation in at least three places throughout their length. Under such conditions when the rest arms are subjected to side thrusts the tendency to rotate is 30 counteracted and the arms are maintained in spaced relation.

Fig. 1 is a perspective view of a folding chair embodying the features of the present invention; 35 and

Fig. 2 is detail view showing the rest arms in folded position.

Referring to the drawing: two angularly disposed bars 10 and 11 are held in spaced relation 40 at opposite ends by rungs or spacers 12 and 13. Two cross bars 14 and 15 are likewise held in spaced relation at opposite ends by similar rungs or spacers 16 and 17. The bar 15 crosses the bar 11 and is pivoted to the inner side thereof by a 45 pivot pin 18. The bar 14 crosses the bar 10 and is likewise pivoted to the inner side thereof by a similar pivot pin 18. A strip of woven fabric 20 which is secured to the rung or spacer 12 passes downwardly intermediate the upper ends of the 50 bars 10 and 11 and then outwardly intermediate the upper ends of bars 14 and 15. The upper ends of bars 10 and 11 and the strip of woven material intermediate thereof constitute the back portion of the chair and the upper ends of bars 55 14 and 15, and the strip of woven material inter-

mediate thereof constitute the seat of the chair. A flat spacer 21 is secured to the upper ends of bars 14 and 15 a slight distance behind the rung of spacer 16. This spacer 21 prevents the strip 20 from sagging too abruptly when the chair is 5 occupied, and also serves to maintain the upper ends of bars 14 and 15 in spaced relation. The lower ends of bars 10 and 11 or those ends below the pivot pins 18 constitute the front legs 10 of the chair, and the lower ends of the cross bars 14 and 15 or those ends below the pivot pins 18 constitute the rear legs of the chair.

To permit the angle of repose of the back of the chair to be adjusted, the upper ends of bars 22 and 23 are pivoted to the outer sides of bars 15 10 and 11 by pivot pins 24 and 25 respectively. The lower end of the bars 22 and 23 are held in spaced relation by a rung or spacer 26. The spacer 26 is adapted and arranged to fit into a plurality of oppositely disposed grooves 27 and 28 which are cut in the upper sides of the lower portions of the bars 14 and 15. To increase the angle of repose of the back the spacer 26 is placed into an upper set of oppositely disposed grooves 27 and 28, and to decrease the angle 25 of repose of the back the spacer 26 is placed into a lower set of oppositely disposed grooves 27 and 28.

Rest arms 29 and 30 are secured to the back 30 of the chair and supported from the seat by supporting members 31 and 32. The inner ends of the rest arms are pivoted to the outer sides of bars 10 and 11 by pivot pins 33 and 34 respectively. The upper ends of the supporting members 31 and 32 are pivoted to the inner sides 35 of the rest arms 29 and 30 by pivot pins 35 and 36 respectively. By this arrangement the upper ends of the supporting members are held in spaced relation and the outer ends of the rest arms are likewise held in spaced relation. The 40 lower ends of the supporting members 31 and 32, that is, the ends which extend downwardly below the seat of the chair, are held in spaced relation by a rung or spacer 37. The supporting members 31 and 32 are also held in spaced 45 relation intermediate the tops and bottoms thereof by being pivoted to the outer sides of the spaced bars 14 and 15. The intermediate sections of the supporting members 31 and 32 are desirably pivoted to the outer sides of the bars 50 14 and 15 by L-shaped plates 38 and 39 respectively. The horizontal legs of the L-shaped plates are secured to the outer surfaces of the spaced bars 14 and 15 by pivot pins 40 and the vertical legs of the L-shaped plates are secured to the 55

inner faces of the supporting members 31 and 32 by pivot pins 42. While the use of L-shaped plates for securing the supporting members to the bars 14 and 15 is desired, other arrangements 5 may be used. For example, the supporting members may be pivoted directly to the bars by pivot pins.

When in use the chair is in the position shown. To fold the chair the spacer 27 is removed from 10 the grooves 28 and 29 and the bars 22 and 23 are swung upwardly about pivot pins 24 and 25 until the bars 22 and 23 are in alignment with the inner sides of the upper ends of bars 10 and 11. The lower ends of bars 14 and 15 are then swung upwardly about pivot pins 18 until the bars 14 and 15 are in alignment with the inner sides of bars 10 and 11. As the lower ends of bars 14 and 15 swing upwardly about pivot pins 18 the upper ends thereof swing downwardly. As the upper 20 ends of bars 14 and 15 swing downwardly the rest arms 29 and 30 also swing downwardly about pivot pins 33 and 34, and the supporting members 31 and 32 pivot at their upper ends about pins 35 and 36 and at their intermediate portions about the L-shaped pivots 38 and 39 until they abut 25 the legs 10 and 11.

The feature of extending the supporting members 31 and 32 downwardly beyond the seat and holding the lower ends thereof in fixed spaced relation prevents the rest arms 29 and 30 from moving sideways when subjected to side thrusts. For example if side thrusts are exerted which tends to move the rest arms outwardly the strains thus produced are transmitted through the supporting 35 members to the spacer thereby subjecting the spacer to compression and as a result the supporting members and associated rest arms do not rotate about where the supporting members are secured to bars 14 and 15. In like manner when 40 the rest arms are subjected to side thrusts which have a tendency to move the side arms inwardly the spacer is subjected to tension and as a result the side arms are maintained in spaced relation.

While the use of a spacer intermediate the lower 45 ends of the supporting members is preferable it is to be understood that other arrangements may be employed, the essential feature in all cases being that the supporting members are main-

tained in spaced relation in at least three places throughout their length.

I claim:

1. In a folding chair two angularly positioned bars disposed opposite one another in spaced relation, spacers positioned between said bars, two angularly positioned cross bars disposed opposite one another in spaced relation and pivotally connected between their ends to said bars, spacers positioned between said cross bars, two oppositely disposed supporting bars pivotally connected at their upper ends to the upper portions of said bars, a spacer member positioned between the lower ends of said supporting bars, a plurality of oppositely disposed grooves in the lower ends of 15 said cross bars adapted to receive said spacer member, rest arms pivotally connected at their inner ends to said bars, supporting members for said rest arms, said supporting members being pivotally connected at their upper ends to the 20 outer ends of said rest arms and maintained in spaced relation at their lower ends by a spacer and connecting members pivotally connected to said supporting members between the ends thereof and to the upper ends of said cross bars. 25

2. In a folding chair two angularly positioned bars disposed opposite one another in spaced relation, spacers positioned between said bars, two angularly positioned cross bars disposed opposite one another in spaced relation and pivotally connected between their ends to said bars, spacers positioned between said cross bars, two oppositely disposed supporting bars pivotally connected at their upper ends to the upper portions of said bars, a spacer member positioned between the lower ends of said supporting bars, a plurality of oppositely disposed grooves in the lower ends of 35 said cross bars adapted to receive said spacer member, rest arms pivotally connected at their inner ends to said bars, supporting members for 40 said rest arms, said supporting members being pivotally connected at their upper ends to the outer ends of said rest arms and maintained in spaced relation at their lower ends by a spacer and L-shaped connecting members pivotally connected to said supporting members between the ends thereof and to the upper ends of said cross bars. 45

AMOS G. PARRY.
